[57] **CLAIM**

The ornamental design for a power tool for laminate trimming and edge finishing, as shown and described.

DESCRIPTION

FIG. 1 is a bottom perspective view of a power tool for laminate trimming and edge finishing showing my new design;

FIG. 2 is a front end elevation view thereof;

FIG. 3 is a rear end elevation view thereof;

FIG. 4 is a left side elevation view thereof;

FIG. 5 is a right side elevation view thereof;

FIG. 6 is a bottom plan view thereof;

FIG. 7 is a top plan view thereof.

The conventional electrical cord has been shown fragmentarily in FIGS. 1, 3 and 5-7 for ease of illustration.
